[57] ABSTRACT

This invention relates to a time-indicating apparatus using neither figures nor pointers, wherein the time-indicating plane is divided into the hour, minute and second indicating sections of a multiple of twelve and electric lamps or the like provided inside said sections are turned on or off by means of a switch connected to the clock mechanism to indicate the time by illuminating said sections successively.

TIME INDICATING APPARATUS

This invention relates to a time-indicating apparatus, more specifically, to a time-indicating apparatus wherein each of the hour indicating areas and the minute indicating areas are divided into 12 sections or its multiple, which constitute the time indicating planes to be illuminated or to emit light by turns.

As conventional time-indicating apparatus, horologe such as clockwork one or electrical one having a dial plate, an hour hand, a minute hand and a second hand to indicate time, have been in general use, apart from sandglasses, water-clocks, etc. The digital horologe in recent fashion indicates time numerically, but it is still difficult to identify time clearly in a dark place or from a distance. With the recent speed-up of traffic facilities, it is needed to identify time in a moment by horologes in or out of the vehicle, further it has become more necessary to identify time at night under the same lux as in the case of illumination. Furthermore, in order to have the existing state of things judged effectively, it is sometimes needed to photograph time at the same time as the on-the-spot photographing in the ground or photographing of other outdoor activities. However, horologes which can safely be used under such circumstances have not yet been in practical use, because of the fact that it has been very difficult technically to design the apparatus which is simple in construction, is usable for a long period of time, yet is provided with a switch means to switch on and off the luminous bodies of a multiple of 12 by turns at a high degree of accuracy.

This invention was made with a view to eliminating the above defects and makes it a prime object to provide a time indicating apparatus which serves also as an illumination device by its glowing, instead of the conventional horologe having an hour hand and a minute hand such as a wall-clock or a table-clock and a digital horologe.

It is another object of this invention to provide a mechanical switch of simple construction which operates accurately to switch on and off the luminous body at each section of a time indicating plane.

It is also another object of this invention to provide a small size alarm clock or a panel clock in which an electric bulb of particular shape, such as triangular one, is employed in each section of the time indicating plane.

It is also another object of this invention to provide a small size time-indicating apparatus of clocks described hereinbefore and having the time indicating board adopting an electroluminescence panel by an electroluminous substance in each section of the time indicating plane.

It is also another object of this invention to provide an electrical time-indicating apparatus whose switch means includes electrical oscillating apparatus and is driven by the pulse of every one minute, of the large size described in the above objects and of the small size made portable by the IC circuit.

It is still a further object of this invention to provide a time indicating apparatus having a time correcting device and being serviceable also as a sign pole or an indoor lantern by indicating time with light and the time indicating plane of which is realizable in quite different shapes such as a pole, a barrel or a street lamp.

Other and further objects of this invention will become apparent upon referring to the drawings in which:

FIG. 1 is a front view of one embodiment of the time-indicating apparatus according to the present invention.

FIG. 2 shows the division of colors for each of the hour indicating sections and the minute indicating sections of the time indicating board of a time-indicating apparatus in FIG. 1.

FIG. 3 is a perspective view of a part of the time-indicating apparatus shown in FIG. 1, from which an upper lid and side plates are removed.

FIG. 4 is a perspective view of a cut-out portion of a time indicating board, showing cut patterns a - e of the surface thereof,

FIG. 5 is a perspective view of the second embodiment of this invention, partly broken away,

FIG. 6 is a longitudinal sectional view of the center of FIG. 5,

FIG. 7 is a front view of the time indicating board of the second embodiment of this invention,

FIG. 8 is a plan view of the switch mechanism connected to the clock mechanism and enclosed in the time-indicating apparatus,

FIG. 9 is a side elevation of the right side of the switch mechanism shown in FIG. 8,

FIG. 10 is a cross sectional view of the switch mechanism, taken on the sectional line 10-10 in FIG. 8.

FIG. 11 is a cross sectional view of the switch mechanism, on an enlarged scale, taken on the sectional line 11-11 in FIG. 8.

FIG. 12 and FIG. 14 are developed views of the rotary switch drum,

FIG. 13 and FIG. 15 are wiring diagrams for the switch mechanism of the rotary switch drum,

FIG. 16 is a front elevation of the disc-shape switch,

FIG. 17 is a side elevation, on an enlarged scale, of the part encircled with a chain line in FIG. 16,

FIG. 18 is a perspective view showing the main portion of a multi-contact point used with an embodiment of this invention,

FIG. 19 is a perspective view of a pawl shaped cam and a ratchet wheel,

FIG. 20 is a developed view of a switching drum,

FIG. 21 is a circuit diagram for indicating the minute,

FIG. 22 is a circuit diagram for indicating the hour,

FIG. 23 is a front elevation of the time indicating board of a fourth embodiment

FIG. 24 is a perspective view of one of the electroluminescence panels shown in FIG. 23,

FIG. 25 is a cross sectional view of the electroluminescence panel, as taken on the sectional line 25-25 in FIG. 24,

FIG. 26 is a circuit diagram for the electroluminescence time indication,

FIGS. 27 - 29 are diagram-illustrating electrical pulses occurring in the embodiment of the invention

FIGS. 30 - 36 are diagrams to explain the fifth embodiment of this invention, in which FIG. 30 is a block diagram combining an oscillating apparatus with a driving section, FIG. 31 is a block diagram of a time correcting section, FIG. 32 is a block diagram of an electric power source apparatus, FIG. 33 is a series-connect diagram of an oscillating apparatus and FIGS. 34-36 are diagrams of signal waves and

FIGS. 37(a) and 37(b) are perspective views of electric bulbs adopted for the time indicating board of the sixth embodiment.

The models and the mechanisms of time-indicating apparatus embodied in this invention are shown hereafter with reference to the accompanying six embodiments wherein the first embodiment represents the whole apparatus of this invention and other modifications of the apparatus of this invention are shown from the second embodiment to the sixth embodiment.

Embodiment 1:

This embodiment is a drum switch of change-over type time-indicating apparatus which is driven by motors. A time-indicating apparatus 51 of square pillar shape in FIG. 1, which being engaged to a wall 53 by support means 52a, 52b, contains therein a clock mechanism 54 and a switch mechanism 55. Its side board 56 is divided into 12 time indicating sections by horizontal lines $S_1, S_2, \dots, S_{11}$ and is also divided by a vertical line 57 into large sections $h_1, h_2, \dots, h_{12}$ and small sections $m_1, m_2, \dots, m_{12}$. Each large section indicates 1 hour, i.e., the uppermost h_1 indicates 1 o'clock ... h_{12} indicating 12 o'clock. By the switch mechanism to be described hereinafter, an electric lamp in each large section is kept lighted for one hour by turns to indicate respective hour. The small area is a minute indicating plane at intervals of 5 minutes. By the switch mechanism 55 to be described hereinafter, electric lamps in small sections are switched on successively at 5-minute intervals from the uppermost section down to the lowermost section and thus electric lamps in all small sections $m_1, m_2, \dots, m_{12}$ are ON with the lapse of 55 minutes but with the lapse of 60 minutes, only the electric lamp at the uppermost m_1 is kept lighted and the other electric lamps are switched off.

FIG. 1 shows that the apparatus indicates 5:15 by the illuminating of h_5 and m_1, m_2 and m_3 . The time indicating board 56 comprising $h_1, m_1, h_2, m_2, \dots, h_{12}, m_{12}$ is colored as shown in FIG. 2, in which the color of h_1, m_1 is grey blue, h_2, m_2 is sky blue, h_3, m_3 is blue, h_4, m_4 is violet, h_5, m_5 is yellowish green, h_6, m_6 is green, h_7, m_7 is ivory, h_8, m_8 is salmon, h_9, m_9 is yellow, h_{10}, m_{10} is orange, h_{11}, m_{11} is pink and h_{12}, m_{12} is red.

As above-mentioned, when the time indicating board 56 is made as a colored board, a transparent board or a plastic board having such patterns or the surface thereof, as shown in FIG. 4 (a)–(e), as diamond cut 4a, angled cut 4b, fluted cut 4c, checkered cut 4d or honeycomb cut 4e is adopted. The reason why these cut boards should be employed is to make the inside invisible, as well as to make it easy to distinguish colors when illuminated. Provided at the inside of each of horizontal lines $S_1, S_2, \dots, S_{11}$ to indicate the time is a partition plate 66 whereby only one large section of $h_1, h_2, \dots, h_{12}$ is illuminated at all times. Thicker sectioning plates 58 are inserted at intervals of three steps to facilitate identifying of the time.

Accommodated in a lower stand 59 of square shape are the clock mechanism 54 which is driven by a small size motor and the switch mechanism 55, which are connected to the electric power source through a cord 60. This small size motor may be replaced by a magnet or a spring according to the installation place. Props 62 are made hollow and lead wire is threaded therethrough. Numeral 63 denotes an electric lamp to illuminate the hour indicating plane. Numeral 64 denotes an electric lamp to illuminate the minute indicating

plane. The time-indicating apparatus 51 is provided with two electric lamps at each section, namely, 24 electric lamps for illuminating $h_1, h_2, \dots, h_{12}$ and further 24 electric lamps for illuminating $m_1, m_2, \dots, m_{12}$. Numeral 65 is a fluorescent lamp arranged at the center of the time-indicating apparatus 51 to illuminate the apparatus as a whole. Numeral 67 denotes a partition plate to avoid the electric lamp in the minute indicating plane from illuminating the hour indicating plane. Partition plates 66 also serve as plates to which electric lamps 63, 64 are fixed. Numeral 61 denotes an upper lid.

An explanation is made below, with reference to FIG. 8, on the switch mechanism which is connected to the clock mechanism to switch on and off the electric lamps inside the time indicating planes in accordance with the lapse of time. FIG. 8 is a plan view of the switch apparatus which successively controls electric lamps inside the hour-indicating plane at intervals of 1 hour and switches on electric lamps inside the minute indicating planes in due order at intervals of 5 minutes. Numeral 71 denotes a shaft of a rotary switch drum 77 which switches on and off the electric lamps inside the hour indicating planes. Numeral 70 is a shaft of a rotary switch drum 72 which switches on electric lamps inside the minute indicating planes in due order. Numerals 78, 79 are support plates to support shafts 70, 71 of these rotary switch drums. If the shaft 70 for the minute indicating is connected to a shaft for the minute indicating of clock mechanism, the shaft 70 makes one revolution for every 1 hour but the shaft 71 for the hour indicating makes one-twelfth revolution for every 1 hour by means of gear mechanism in which a gear 80 connected to the shaft 70 for the minute indicating is engaged with a gear 81 connected to the shaft 71 for the hour indicating. If the second indicating plane is to be arranged, the shaft for the second indicating is connected to a shaft for the second indicating of clock mechanism or a new shaft for the second indicating is added by the multiplying gear from the minute indicating shaft 70. A 12-step good conductor board 75 is put on the rotary switch drum 72 in order to switch on electric lamps inside the minute indicating plane in due order at intervals of 5 minutes. If it is desired to switch on electric lamps 64 in due order at intervals of 1 minute, a 60-step good conductor board should be put on the rotary switch drum. $Sm_0, Sm_1, \dots, Sm_{12}$ are L type contact pieces of good conductor. These contact pieces press lightly the rotary switch drum 72 for the minute indicating and are fitted to the stand plate with small screws 68a. Each of L type contact pieces $Sm_0, Sm_1, \dots, Sm_{12}$ is connected to the electrode with respective electric wire 69a. The L type contact piece Sm_0 is connected to the cathode. As the good conductor plate 75 which makes contact with Sm_0 is put on all the circumference of the rotary switch drum 72 for the minute indicating, it is cathodic at all times. Contact pieces $Sm_1, Sm_2, \dots, Sm_{12}$ are connected to the anode through electric lamps 64 for the minute indicating. In FIG. 8, all of the 13 L type contact pieces $Sm_0, Sm_1, \dots, Sm_{12}$ are in contact with the rotary switch drum 72 for the minute indicating but as the surface of said drum which is in contact with $Sm_2, Sm_3, \dots, Sm_{12}$ is made of insulator board 73a, Sm_0 and Sm_1 are in the condition of insulation from $Sm_2, Sm_3, \dots, Sm_{12}$. The rotary switch drum 72 for the minute indicating in FIG. 8 corresponds to the case where it is illuminating the uppermost m_1 in

FIG. 1. A good conductor board 74 is put on all the surface of a rotary switch drum 77 for the hour indicating function. An insulator board 73b is put on the surface of said good conductor board 74, excepting the part where it makes contact with the L type contact piece Sh₀. Square contact pieces 76, 76, . . . parts of which are attached to conductor board 74 are attached to the surface of said insulator board 73b, as indicated by FIG. 11, with the shift by one-twelfth revolution. L type contact pieces of good conductor Sh₀, Sh₁, . . . Sh₁₂ press lightly the rotary switch drum 77 for the hour indicating and are fixed to the stand plate with small screws 68b. Each of L type contact pieces Sh₀, Sh₁, . . . Sh₁₂ is connected to the electrode by electric wire 69b. The good conductor board 74 is connected to the cathode through the L type contact piece Sh₀. As said good conductor board 74 and square contact pieces 76, 76 . . . are connected as mentioned hereinbefore, twelve square contact pieces, 76, 76 . . . are always cathodic. L type contact pieces Sh₁, Sh₂, . . . Sh₁₂ are connected to the anode through electric lamps 63 for illuminating the hour indicating plane. The rotary switch drum 77 in FIG. 8 corresponds to the case where the square contact piece and Sh₁ are in contact and h₁ (1 o'clock) in FIG. 1 is illuminated. With the revolution of the rotary switch drum 77 for the hour indicating, the L type contact piece Sh₁ and the square contact piece are separated but at the same time the L type contact piece Sh₂ and the succeeding square contact piece make contact with each other, in other words, the electric lamp inside h₁ is switched off but at the same time the electric lamp inside h₂ is lighted. Thus, at every one-twelfth revolution of the rotary switch drum 77 for the hour indicating, electric lamps inside the hour indicating plane are switched on and off in due order to indicate the hour. The arrow L indicates the direction in which the rotary switch drum revolves. 86a and 86b are electric power sources.

Referring to the rotary switch of disc shape which are substitute the above-mentioned drum-shape rotary switch, an explanation is made below, with reference to FIG. 16 and FIG. 17. Numeral 87 denotes a rotary disc supported with support plates 90, 91 fitted to a rotary shaft 89 which is connected to any one of the hour-shaft, minute-shaft and second-shaft of clock mechanism. Put on the inner surface of said rotary disc 87 is a good conductor board 94, to which two contact pieces 92, 93 of good conductor are fitted. The good conductor board 94 is in contact with a L type contact piece 95 of good conductor which is connected to the cathode. Numeral 88 denotes a fixed disc provided oppositely to the rotary disc 87. A plate composed of good conductor board E₁, E₂, . . . E₆ and insulator boards I₁, I₂, . . . I₆ is put on the inner surface of the fixed disc 88.

Good conductor boards E₁, E₂, . . . E₆ are connected to the anode through electric lamps 96, 96 . . . E₁ and E₂, E₃ and E₄, and E₅ and E₆ are connected by contact pieces E₁₂, E₃₄ and E₅₆ respectively so that they are made the same electrode in pairs. On the circumference of the fixed disc 88 are formed electrodes of a multiple of 12. Numeral 97 is an electric power source. The distance D₁ between the two contact pieces 92, 93 of good conductor is equal to the sum of the width D₃ (of insulator boards I₁, I₂, . . . I₆) and the width D₂ (of insulator boards I₇, I₈, I₉), i.e., D₁=D₂+D₃. When either of contact pieces 92 and 93 of good conductor makes

contact with either of electrodes E₁ and E₂ either of electrodes E₃ and E₄, either of electrodes E₅ and E₆ . . . and the contact piece 92 shifts to the succeeding electrode E₃, even if continuity of circuit is broken by passing the insulator board I₁, the contact piece 93 makes contact with the succeeding electrode E₃ to compensate continuity and keep the electric lamp 96 lighted. Thus, the disc shape rotary switch according to this invention is not bulky but compact and keeps the electric lamp 96 inside the time indicating plane lighted at the change of time indicating plane. As the rotary switch drum 77 for the hour indicating revolves at a very slow speed, i.e., one revolution for every 12 hours or one-twelfth revolution per hour, it involves technical difficulty to shift instantaneously the contact with any electrode to the succeeding electrode. To avoid contacting with two electrodes at the same time or separating from two electrodes at the same time, the following method is adopted. As indicated by FIG. 10, a gear 81 with 12 teeth connected to the shaft 71 for the hour indicating is engaged with a gear 80 having only one tooth of the same module as the teeth of said gear 81 and connected to the shaft 70 for the minute indicating. Under this arrangement, while the shaft 70 for the minute indicating makes one revolution, the shaft 71 for the hour indicating makes one-twelfth revolution, namely, the time required for the shaft 71 for the hour indicating to make one-twelfth revolution is 5 minutes and the shaft 71 is kept standing for the remaining 55 minutes because the gear 80 for the minute indicating has only one tooth. The gear 81 connected to the shaft 71 for the hour indicating may have 24 teeth. In this case, the time during which there is danger of two square contact pieces and a L type contact piece touch or separate at the same time, can be minimized. Setting of the minute at starting can easily be done if gears 80 and 81 are made movable manually.

Embodiment 2

40 This embodiment is an example of a time-indicating apparatus having the pattern at the surface as shown in FIG. 4 and which is serviceable as the box-shaped sign pole.

As shown in FIG. 5, a time-indicating apparatus 51a is shaped like the box by the time indicating board of the front plane 56a, the back plane 56a and the side planes 102. The hour indicating area h₁ to h₁₂ is divided from the minute indicating area m₁ to m₁₂ by an annular band 98 and the two areas are divided into h₁, h₂, . . . h₁₂ and m₁, m₂, . . . m₁₂ respectively. The inside of said time-indicating apparatus is divided into the desired number of sections with the curved cover segment 99 and radial cover segment 100 so that each section of said time indicating board 56a may be illuminated individually and hour indicating lamps L₁, L₂, . . . L₁₂ and minute indicating lamps l₁, l₂, . . . l₁₂ are disposed in each chamber. The other constructions of this embodiment are the same as of the first embodiment. Numeral 127 is a leg of the time-indicating apparatus 51a for use when it is erected on the roof of a building. The time-indicating apparatus 51a is made in such a manner that the time indicating boards 56a and the advertisement side boards 102 are illuminated by a common fluorescent lamp 101 for illuminating each chamber thereof. FIG. 7 shows, on the time indicating board 56a, the colored period of time from 5:15 to 5:20.

Embodiment 3:

This embodiment (shown in FIG. 18) is another one example of the switching mechanism described in the first embodiment of this invention and this switching mechanism is provided with desired function and with a simple construction for operating in scale of 12 circuit of double-stage type by the input and therefore can be employed, with the pulse obtained by a small size motor or an oscillator used as the input, for the driving section such as of the time-indicating apparatuses 51, 51a. On the lower side of a plate 103 is a magnet 104 which operates by pulse from the outside. An end portion of an attraction piece 105 of said magnet is connected to the center of a driving lever 106 on said plate 103.

A switching mechanism 107 is composed of the following three parts: a ratchet wheel 107a, a drum portion 107b which has 12 steps 107d molded from an insulating material on the periphery of the cylinder at the interval of the angle 30° and a driving pawl 107c. Said switching mechanism 107 may be molded as one body from an insulating material, such as hard plastics. Said switching mechanism 107 is supported by a shaft 107e between the plate 103 and a plate 109 which are connected with the supports 108a, 108b, 108c and 108d and is fixed to afore-mentioned driving lever 106. The switching mechanism 107 makes one side revolution by a flexible pawl 110 to engage with the ratchet wheel 107a and by a check pawl 111 to engage with said ratchet wheel 107a. Twelve switching arms A₁, A₂, . . . A₁₂ are insulated by a shaft 112 of insulating material and collars 117 and are mounted on said shaft, each corresponding to respective step 107d of the drum portion 107b of said switching mechanism 107.

A contact support plate 113 on which contact pieces G₁, G₂, . . . G₁₂ are arranged is disposed in such a manner that each of said contact pieces G₁, G₂, . . . G₁₂ always contacts with respective switching arms A₁, A₂, . . . A₁₂ and acts as a spring to have said switching arms A₁, A₂, . . . A₁₂ contact with the surface of said drum portion 107b.

A common contact piece 114a attached to a plate 114 is arranged in such a manner that the switching arms A₁, A₂, . . . A₁₂ contact with the common contact piece 114a when they are lifted on the step 107d of said drum portion 107b. A driving pawl 107c of the switching mechanism 107 is engaged with a ratchet wheel 115, at the under side of the upper plate 109, having 12 teeth on the same plane as said pawl 107c.

A rotary contact piece 118, which makes contact by turns with 12 points of contact K₁, K₂, . . . K₁₂ arranged on the periphery with a shaft 115a of said ratchet wheel as a center, is secured to the shaft 115a of said ratchet wheel 115 through the upper plate 109 and a contact plate 116 with printed wire which is fixed on said upper plate 109.

Said contact pieces G₁, G₂, . . . G₁₂ and 114a are connected internally to terminals B₁, B₂, . . . B, Bcom, respectively of a terminal plate 119 and said contact points K₁, K₂, . . . K₁₂ and Kcom are connected respectively to terminals F₁, F₂, . . . F₁₂ and Fcom respectively of a terminal plate 120, and thus wiring with the other parts of the apparatus is facilitated. With reference to an embodiment in which this device is employed for the time-indicating apparatus, a description is made hereinafter on the mechanical movement of the switch mechanism having the above described construction and the electrical circuit therefor.

FIG. 21 and FIG. 22 show a switching circuit made by the mechanism by this device and FIG. 20 shows, by the developed view of the drum portion 107b of the switching mechanism 107, the condition of the connections of switching arms A₁, A₂, . . . A₁₂ and the condition of ON-OFF of the circuit. A circuit including lamps L₁, L₂, . . . L₁₂ in FIG. 22 is the hour indicating portion 126 and a circuit including lamps l₁, l₂, . . . l₁₂ in FIG. 21 is the minute indicating portion 125 at the interval of 5 minutes. L and l are luminous bodies either of the electrical type such as a lamp or of the electron type such as electroluminous body.

As shown in FIG. 18, a switching cam 121 directly connected to a motor shaft which makes one revolution every 5 minutes, works on a circuit switch 122 of the magnet 104. Thus the magnet 104 makes an attraction operation every 5 minutes. With the movement of said magnet 104, an attraction piece 105 of said magnet moves a driving pawl 110 by a driving lever 106 and said pawl 110 moves one tooth of the ratchet wheel 107a, whereupon the switching mechanism 107 makes one-twelfth revolution. On opening of the circuit of the magnet 104, the attraction piece 105, the driving lever 106 and the pawl 110 get back to their original position by springs 123 and 124. This movement is repeated at every movement of the magnet 104 and the switching mechanism 107 makes an intermittent revolution by the angle of 30° or one-twelfth revolution each time. Switching arms A₁, A₂, . . . A₁₂, according to said intermittent revolution, are pushed on an oblique line portion 107b' of the drum portion 107b (refer to FIG. 20) to make contact with the common contact piece 114a. On the other hand, the switching A₁ is always on the oblique line portion 107b' of the drum portion 107b and always keeps contact with the common contact piece 114a. When the drum portion 107b accomplished one revolution while making intermittent revolutions, switching arms A₂, . . . A₁₂, excepting A₁, are separated at the same time from the drum portion 107b' and are separated from the common contact piece 114a. At this stage, the driving pawl 107c of the switching mechanism 107 moves one tooth of the ratchet wheel 115, whereby a rotary contact piece 118 makes one-twelfth revolution and the contact position is moved from the contact point K₁ to the contact point K₂.

The circuits shown in FIG. 21 and FIG. 22 work by the mechanical movement hereinbefore described. In respect to the circuit of the minute indicating portion at the interval of 5 minutes, a circuit indicating the time 0-5 minutes is always kept broken and with the lapse of every 5 minutes other circuits are successively broken in the order of the circuit l₂ of 5-10 minutes indicating portion, the circuit l₃ of 10-15 minutes indicating portion . . . the circuit l₁₂ of 55-60 minutes indicating portion. Immediately after the circuit l₁₂ of 55-60 minutes indicating portion is broken, the circuit l₂ . . . l₁₂ are opened simultaneously and the circuits from the rotary contact piece 118 of the circuit of hour-indicating portion 126 moves from the circuit L-1 to L-2. This means that hour indicating portion 126 makes one-half cycle at every one cycle of minute indicating portion 125 at the interval of 5 minutes and 12 cycles of said minute indicating portion coincides with one cycle of hour indicating portion. Lamps L₁, L₂, . . . L₁₂ shown in FIG. 22 are fixed to the inside of the hour indicating sections h₁, h₂, . . . h₁₂ of the time indicating portion 126.

cating board shown in FIG. 23 and lamps $l_1, l_2, \dots, l_{12}$ shown in FIG. 21 are fixed to the inside of the minute indicating sections $m_1, m_2, \dots, m_{12}$. Numeral 128 denotes an electric power source.

On the time indicating board 56a, hour indicating panels $h_1, h_2, \dots, h_{12}$ are illuminated by turns, which is combined with the successive illumination of minute indicating panels $m_1, m_2, \dots, m_{12}$ while m_{12} is emitting light, all panels from m_1 to m_2 emit light but with the lapse of 5 minutes from the beginning of lighting of m_{12} , illumination of all panels from m_1, m_2 to m_{12} goes out. At this moment, if h_3 is lighted, it is shifted to illumination of h_4 .

Embodiment 4:

This embodiment is an example of the construction of an electroluminescence panel which is employed as a time indicating board 56b of a time-indicating apparatus 51b. The driving section is made by an electric circuit, however, it can be replaced to the switching mechanism of the above-mentioned, third embodiment. FIG. 23 illustrates a time indicating board of circular type. Sections $h_1, h_2, \dots, h_{12}$ or an inner circle divided into 12 equal parts is an hour indicating area and sections $m_1, m_2, \dots, m_{12}$ or an annular space divided into 12 equal parts is a minute indicating area. Each section composes an individual electroluminescence panel. One of the sections h_1 or electroluminescence panel is shown in FIG. 24 and FIG. 25. Numeral 131 denotes an electroluminous substance layer, at both sides of which are laid transparent electrodes 132, 132. The outer peripheral edge of electroluminous substance layer 131 is covered with a spacer 133. Laid outside of each transparent electrode layer 132 is a transparent glass layer 134. Connected to the ends of transparent electrode layers 132, 132 are lead wires 135, 136. Each electroluminescence panel is connected as shown by the electroluminescence time-indicating apparatus circuit of FIG. 26 and is impressed with voltage, whereby the time indicating board 56b works. Numeral 138 denotes the oscillating section of electroluminescence time indicating circuit. The time constant which determines frequency by using temperature-compensating resistance and condenser, is adapted so as not to be changed by temperature. The oscillating section has a multi-vibrator type low frequency oscillator. Numeral 139 is a frequency stepdown section, to which a flip-flop circuit is cascade-connected. Numeral 140 is a pulse amplifying section, whereby the pulse stepped down at the section 139 is amplified enough to actuate the succeeding scale of 12 counter section 141. Each of $m_1, m_2, \dots, m_{12}$ of the minute indicating panel area 142 is connected with respective silicon control element 144, through the medium of a 12-core cable 145. Numeral 143 denotes a switching section. If an electric current is applied to the gate of the silicon control 144 and is triggered, the principal electric current flows continuously. This principal electric current is made OFF at the switching section 143.

In the hour indicating panel section 147, numeral 146 is a scale of 12 counter section; numeral 148 is a switching section; numeral 149 is a silicon control element; numeral 150 is a 12-core cable. The electric power source section 151 is connected to the switching sections 143, 148. The scale of 12 counter sections 141, 146 have scale of 12 ring counters and introduce voltage which is gradually transferred from twelve output terminals by pulse impression. Switching sections 143,

148 have a non-contact switch circuit, wherein a phase inverting circuit is connected to the base of transistor.

Pulse P from the oscillating section 138 is a low frequency of ΔH time width as indicated by FIG. 27. Pulse P from the frequency stepdown section 139, as indicated by FIG. 28, is made a cycle of 5-minute and becomes the pulse of high tension at the pulse amplifying section 140, as shown by FIG. 29.

Principal electric current of the silicon control element 144 which was triggered so as to maintain the luminescence of each of $m_1, m_2, \dots, m_{12}$, is made OFF at the same moment as the buildup of pulse from the output terminal of the scale of 12 counter section 141 and is made to flow through the medium of the switching section 143. Then, immediately after the switching section 143 is made ON, m_1 alone is made to emit light. In the luminescence of the hour indicating panel section 147, triggering is effected after luminescence of $h_1, h_2, \dots$ and the principal electric current 149 of silicon control element is made OFF at the same moment as the buildup of pulse from the output terminal of the scale of 12 counter 141 and is made to flow through the medium of the switching section 148. The output terminal of the scale of 12 counter section 141 is connected to the scale of 12 counter 146 and is synchronized with the afore-mentioned relation between the minute indicating panel 142 and the hour indicating panel 147.

On the time indicating board 56b, hour indicating panels $h_1, h_2, \dots$ are illuminated by turns, which is combined with the successive illumination of minute indicating panels $m_1, m_2, \dots$ and while m_{12} is emitting light, all panels from m_1 to m_{12} emit light but with the lapse of 5 minutes from the beginning of lighting of m_{12} , illumination of all panels from m_2 to m_{12} goes out. At this moment, if h_3 is lighted, it is shifted to illumination of h_4 . Numeral 152 is a switch for regulating the time indication.

Liquid crystal can be used as electroluminous substance. In this case, the panel section is lighted by impression of voltage to indicate the time. In the foregoing embodiment, the minute is indicated by the intervals of 5 minutes but this can be changed to the indication at intervals of one minute by increasing electroluminescence panels. Therefore, if this device is applied to a watch, it facilitates reading of time or it offers easier reading of time than in the case of conventional watches.

Embodiment 5:

This embodiment shows one example of an oscillator for driving a time-indicating apparatus which comprises a plural of standardized original oscillators such as tuning forks or crystals and an electric circuit.

The oscillator in this embodiment can be adopted to the driving section of the time-indicating apparatus 51 in the first embodiment together with the switching mechanism in the third embodiment.

The construction of this embodiment, as shown in FIG. 30, relates to the oscillator 161 for driving the time-indicating apparatus characterized in that original oscillator 162a, 162b of the standard frequency such as a plurality of tuning forks or crystals, a 1/5 step-down circuit 181 for obtaining the signal 182 of every 5 minutes, 1/12 step-down circuit 183 for obtaining the signal of therethrough and an amplitude regulating circuit 165 are connected.

The original oscillators 162a, 162b are of the wave of the output shown in FIG. 34 and the sum or the difference of the first, second and fourth embodiments of this invention. An adder 163 is to amplify the voltage of the output of each oscillator 162a, 162b which is added at every moment and this output becomes the wave of the output as shown in FIG. 35, whereby the signal which corresponds to the sum or the difference of frequencies of the original oscillators 162a, 162b appears.

This means that 1Hz of signal is included in the output. This output is given to a band-pass filter circuit 164. This band-pass filter circuit 164 works only to pass therethrough the signal having the number of oscillation close to 1Hz and can pick up only the signal of 1Hz among signals obtained by the adder 163 and output wave thus produced is shown in FIG. 36A. Furthermore, to obtain signals such as one minute and one hour, a step-down counter should be operated. A wave shaping circuit shown in FIG. 36B is provided by an amplitude regulating circuit 165 in order to produce desired wave of output by said step-down counter. Output signal thus shaped becomes a signal of every 1 second of 1Hz. This signal 166 becomes the signal 168 of every 1 minute by being passed through a scale of 1/60 step-down counter 167 by the passage of (a) in FIG. 30, and further the signal 168 becomes the signal 170 of every 1 hour by being passed through a scale of 1/60 step-down counter 169. Time correcting part 171 is connected to the scale of 1/60 step-down counters 167, 169.

The change-over switch for illuminating the luminous body is operated by signals 166, 168, 170 of a driving section 172 respectively for every second, every minute and every hour.

The above-mentioned signal 166 of 1Hz is connected with a 1/5 step-down circuit 181 for obtaining the signal of every 5 minute, 1/12 step-down circuit 183 for obtaining the signal of one hour and time correcting section 171 by the passage of (b) in FIG. 30. These step-down circuits can be connected with the switching mechanism of the time-indicating apparatuses 51, 51a and 51b in the first and the second embodiments by this invention.

Generally, when a plurality of oscillators oscillating at about the same number of oscillation are combined mechanically or electrically, oscillators draw each other and present the pull-in phenomenon. In order to eliminate this combination, this invention adopts an adding amplifier, the principle of which is the same as that being employed in an analogue computer, whereby the combination is minimized and the pull-in phenomenon is avoided.

The characteristic of temperature and the characteristic of change with the lapse of time are made efficient if they are properly selected according to this invention because this invention adopts the signal corresponding to the sum or the balance of each oscillator, however, the irregularity of the number of vibration of the signal can not better be revised that of the original oscillator. But by replacing the parts for which a counter has been used connectionally with the apparatus by this invention, the number of component parts can be reduced. Furthermore, the apparatus by this invention can be made at low cost and is efficient in the characteristic of temperature and the characteristic of change with the lapse of time. Furthermore, the apparatus by this invention

can be easily installed in the I.C. mechanism and can be of a small size and it can be available as a common clock for household use or a portable clock.

The oscillator 161 having the above described construction is embodied in the series connect diagram of FIG. 33.

Tuning forks TFa, TFb are about 28mm in the total length, and constitute an oscillation circuit of approximate 2,000Hz in combination with transistors Tr1, Tr2.

10 The load of a collector is given in such a manner that the capacity and the resistance are connected in parallel and thus the parasitic oscillation caused by the higher frequency than 2,000Hz is prevented. Ct is an adjusting part to make the balance of the frequency of two oscillators 1Hz. Variable resistances VR1 and VR2 are to adjust the strength of the oscillation made by tuning forks TFa, TFb. An adding amplifier and the band-pass filter circuit 164 to pass 1Hz therethrough are constructed by resistances R1, R2, R3, R4, condenser C3 and transistor Tr3. The circuit which allows only 1Hz to pass therethrough is constructed when the operating point of the transistor Tr3 is made the condition of cut-off and R4 and C3 are given as load. Resistances R1, R2, R3 and R4 and the transistor Tr3 construct an adding amplifier, the same as that of an analogue computer, though not so precise. Transistor Tr4 shapes waves and Tr5 forms the output circuit (not always necessary).

30 A time correcting part 171 is, as shown in a block diagram in FIG. 31, comprises a radio receiver 173, a time signal resonance circuit 174, a detector 175 and a pulse amplifying circuit 176 and corrects a driving part 172 at regular intervals by utilizing signal 880Hz of a radio time signal.

35 FIG. 32 is a block diagram of an electrical power source means 177 added to the apparatus in this invention when it is employed both for alternating and direct currents and comprises a rectifying circuit 178, a smoothing circuit 179 and secondary battery 180.

40 An oscillator for driving a small size time-indicating apparatus such as a wrist-watch can be produced if the electric circuit part of the above apparatus is made by the I.C. circuit.

Embodiment 6:

45 This embodiment relates to a time indicating board in which small size electric bulbs in particular shape are employed for each section thereof, particularly, to a time indicating board in which electric bulbs 185a, 185b of particular shapes shown in FIG. 37 (a) (b) are employed in stead of each electroluminescence panel of the time indicating board 56b employed in the fourth embodiment.

50 The electric bulb 185a in FIG. 37(a) is employed for each section of $h_1, h_2, \dots, h_{12}$ of the hour indicating area, and the electric bulb 185b in FIG. 37(b) is employed for each section of $m_1, m_2, \dots, m_{12}$ of the minute indicating area. Numeral 186 indicates a colored transparent top portion made of glass, numeral 187 indicates electrode and numeral 188 indicates the filament. 55 This time-indicating apparatus is fit for a car clock to be fixed to the instrument board in a car.

60 The time-indicating apparatuses described in the first and the second embodiments have such advantage that time can be easily identified even at a dark place or from a distance and is convenient especially for people of poor sight or infants. Particularly a wide indicating plane, a multiplied number of indicating plane or an in-

dicating plane visible from every angle can be provided by one set of a clock mechanism and a switching mechanism. Moreover, even if figures of indicating board are reflected in a mirror, there is no inconvenience to identify time by the apparatuses in this invention.

Furthermore, it can be photographed even at a dark place, time can be identified in a ground at night or time can be photographed at the same time as the on-the-spot photographing in the ground by the apparatuses in this invention. Furthermore, utilizing the time-indicating apparatus of the present invention as lighting equipment makes daily life convenient and serviceable.

Furthermore, the time-indicating apparatus by this invention serves to identify time at night and to drive safely if it is employed in the driver's seat of various vehicles and it is also utilized as ornaments.

The switching mechanism described in the third embodiment can be facilitated accurately by opening and closing of a magnet and therefore can be widely adopted for modifications of this.

The time-indicating apparatus by the electroluminescence panel in the fourth embodiment can be realized both as a small size watch such as a wrist-watch and as a large size clock such as a wall clock.

The oscillator for driving the time-indicating apparatus in the fifth embodiment is of high preciseness because of precise pulse-oscillating compensated with temperature by a plural of standard oscillators.

The time indicating board described in the sixth embodiment is convenient to make the time-indicating apparatus compact.

Various new time-indicating apparatuses can also be provided by combining the time indicating board, the switching mechanism, the motor, the pulse oscillating means and the driving section of the above described embodiment.

It is thought that the invention and many of its attendant advantages will be understood from the foregoing description and it will be apparent that changes and variations may be made without departing from the spirit and scope of the following claims.

What I claim are:

1. A time-indicating apparatus comprising at least one time-indicating body, said time-indicating body comprising chamber-like illumination cells having front surfaces, said cells being arranged for displaying the time by displaying the hour and minute of the day, said hour and minute being displayed by successively controlled electric signals supplied to the respective illumination bodies of said illumination cells, the front surfaces of the illumination cells being provided with crystal-like cut patterns, the electric signals supplied to the illumination bodies of illumination cells illuminating the hour indication for the duration of an entire hour and successively changing to the next hour indication, the electric signal supply to the illumination bodies of the illumination cells illuminating the minute indication cumulatively with illuminating successive minute indications until a change in the hour indication occurs.

2. A time-indicating apparatus as set forth in claim 1 wherein the front surfaces of said illumination cells with said crystal-like cut patterns are interchangeable.

3. A time-indicating apparatus as set forth in claim 1 wherein said chamber-like illumination cells are provided with different colors for said front surfaces to facilitate viewability of said apparatus to determine the time.

4. A time-indicating apparatus as set forth in claim 1, comprising a fixed disc, a plate composed of a plurality of insulator boards and a plurality of good conductor boards, said plurality of insulator boards and said plurality of conductor boards being multiples of ten and being placed on the circumference of said fixed disc, a rotary disc located opposite said fixed disc, said rotary disc having first and second contact pieces, said contact pieces being good conductors, said contact pieces being separated by a distance equal to the sum of the widths of pairs of insulator boards, a plurality of rotary shafts corresponding to the hour minute and second of the day, said rotary disc being connected to any of said plurality of rotary shafts, and a switch located between said fixed and rotary discs.

5. A time-indicating apparatus as set forth in claim 1 comprising a rotatable gear for hour-indicating having a number of teeth equal to a multiple of 12, a gear for minute indicating engageable with said gear for hour indicating, said gear for minute indicating having a number of teeth equal to the multiple of twelve of the number of teeth on said hour-indicating gear.

6. A time-indicating apparatus as set forth in claim 1, wherein a multi-contact point switch having a ratchet wheel with 12 teeth is threaded to one end of a drum, said teeth being rotatable by means of a feed pawl secured to a driving lever driven by an attraction piece intermittently attracted by a magnet, a stepped plate having 12 steps being secured to the surface of said drum, 12 switching arms being disposed in contact with the surface of the drum, each of said 12 switching arms corresponding to a respective step of said stepped plate, a common contact piece being disposed in a position to make contact with said switching arms when said switching arms are pushed by said stepped plate, a pawl-shaped cam being threaded at the other end of said drum, said ratchet wheel being arranged so that it makes one twelfth of a revolution for each revolution of said cam, and a rotary contact piece for contacting said 12 contact points, said rotary contact piece being secured to the shaft of said ratchet wheel.

7. A time-indicating apparatus as set forth in claim 1, comprising a time-indicating board wherein transparent electrodes are placed at both sides of an electroluminous substance layer, a first electroluminescence panel, a second electroluminescence panel, said first and second panels covering the periphery of said transparent electrodes and being respectively disposed at the hour and minute indicating areas, time being indicated by the illumination of electroluminescence panels in the hour and minute indicating areas by illuminating the electroluminous substance with a pulse voltage being applied to each electroluminescence panel.

8. A time-indicating apparatus as set forth in claim 1, comprising an oscillator circuit having a plurality of frequency generating means, an adder connected to receive at least a plurality of input signals of different frequencies, a band-pass filter connected to said adder to allow only signals having a predetermined frequency to pass therethrough, and an amplitude regulating circuit connected to the output of said band-pass filter.

9. A time-indicating apparatus as set forth in claim 1 comprising a time-indicating board having a plurality of hour-indicating sections, each of the hour-indicating sections, each of the hour-indicating sections having the same color as each of the corresponding minute-indicating sections, each of the hour-indicating sections

having different colors from the other of the hour-indicating sections, said time-indicating board being provided with crystal-like cut patterns, said cut patterns being located on the color transparent surface thereof.

10. A time-indicating apparatus as set forth in claim 1, wherein said time-indicating body comprises two sections, a first of said two sections displaying the hour of the day and the second of said two sections displaying the minute of a day, said sections being linearly dis-

10 played.

11. A time-indicating apparatus as set forth in claim 1 wherein said time-indicating body comprises two sections, a first of said two sections displaying the hour of the day and the second of the two sections displaying the minute of the day, said two sections being co-axial with said hour display being located within said minute display.
